UNITED STATES PATENT OFFICE.

EDWARD Y. MOORE, OF MILWAUKEE, WISCONSIN, AND RICHARD W. LUNDY,
OF SOUTH BEND, INDIANA.

DESIGN FOR A FRAME FOR DOOR-HANGERS.

SPECIFICATION forming part of **Design No. 23,940**, dated January 1, 1895.

Application filed May 19, 1893. Serial No. 474,838. Term of patent 14 years.

To all whom it may concern:

Be it known that we, EDWARD Y. MOORE, of Milwaukee, in the county of Milwaukee and State of Wisconsin, and RICHARD W. LUNDY, of South Bend, in the county of St. Joseph and State of Indiana, have invented and produced a new and original Design for a Frame for Door-Hangers, of which the following is a description, reference being had to the accompanying drawing, which is a part of this specification.

The single figure in the drawing is a side elevation of the frame for a door hanger, and fully illustrates our design.

The leading feature of our design consists of the shape or general configuration of the frame, and includes straight flat bars at the top; a curved and somewhat U-shaped strap partially in front of and continuing downwardly somewhat below the bar aforesaid about centrally thereof; a straight flat stem part continuing from the curved strap centrally at a right angle to the bar aforesaid; a flat straight bar or strap below opposite and parallel with the first described bar; and wing pieces having curved edges, above the bottom strap continuing therefrom alongside the stem part toward the U-shaped strap.

The design more specifically includes the

straight flat bar A at the top, the flat surface 30 of which is seen in the drawing in elevation, as also the parallel bar at the rear, between which bars at the rounded ends are pieces of which only the top straight edges appear in the drawing; the curved and somewhat U-shaped strap B, the short parallel legs of which are in front of the bar A, the strap continuing downwardly from the bar centrally forming a space between the curved part of the strap and said bar; the flat part 40 C continuing downwardly from the strap B centrally at a right angle to the bar A, the part C being narrowed near its lower extremity; the straight flat strap D opposite and parallel to the bar A; and the wings E E 45 having curved upper edges, above the strap D, continuing therefrom upwardly alongside the part C toward the strap B.

What we claim as our invention is—

A design for a frame for a door hanger, as 50 shown and described.

In testimony whereof we affix our signatures in presence of two witnesses.

EDWARD Y. MOORE.
RICHARD W. LUNDY.
